UNITED STATES PATENT OFFICE.

EDDIE B. HAGOOD AND WILLIE D. ROLLINGS, OF HINKLEVILLE, KENTUCKY;
SAID ROLLINGS ASSIGNOR TO SAID HAGOOD.

HAME.

SPECIFICATION forming part of Letters Patent No. 687,825, dated December 3, 1901.

Application filed May 4, 1901. Serial No. 58,752. (No model.)

To all whom it may concern:

Be it known that we, EDDIE B. HAGOOD and WILLIE D. ROLLINGS, citizens of the United States, and residents of the town of Hinkle-
ville, county of Ballard, and State of Ken-
tucky, have invented certain new and useful
Improvements in Hames, of which the following
is a specification.

The object of our invention is to provide
an attachment for hames whereby the tug-
fastening is adjustable vertically upon the
hames; and with this and minor objects in
view our invention consists of the parts and
combination of parts, as will be hereinafter
more fully set out.

In the drawings, Figure 1 is a perspective
view of a hame with our invention attached.
Fig. 2 is a front elevation of the same. Fig.
3 is a transverse section on the line *a a*, Fig.
2. Fig. 4 is a perspective view of the sliding
member.

In the drawings, 1 represents a hame of ap-
proved construction.

2 is a groove cut in the face of the hame.
25 3 is a plate having an elongated slot 4, said
plate being secured on the face of the hame
by suitable screws or other desired means im-
mediately over the slot 2 formed in the hame.
The elongated slot in the plate 3 is narrower
30 than the slot or groove formed in the hame,
whereby the edges of the slot 4 overhang the
slot 2 in the body of the hame, as clearly
shown in Fig. 3.

35 14 represents series of openings formed
through the plate 3 on one side of the elon-
gated slot, to be hereinafter referred to.

40 5 is a plate, from the sides of which extend
suitable wings 6, said wings being of less
thickness than the plate 5, thereby forming
a substantially T-shaped body.

45 7 represents lugs extending upwardly from
the plate 5 and projecting beyond each side
of the plate 5 to a point beyond the outer
edges of the wings 6, as clearly shown in Figs.
3 and 4.

50 8 is a lug extending from the side of one of
the lugs 7 above the plane of the top of the
plate 5 and provided with a suitable perfora-
tion 9.

55 10 is a tug-hook secured between the lugs
7 by means of the pin 11. The upper end of

the elongated slot is opened, as at 12, as shown
in the several figures.

In assembling the parts the slidable mem-
ber, comprising the plate 5, wings 6, lugs 7 55
and 8, is slid into the slot 4 of the plate 3.
The wings 6 extend beneath the plate 3 on
each side of the slot 4, while the extreme
ends of the lug 7 extend above the plate 4 be-
yond each side of the slot, as seen in Fig. 3. 60
The plate 3 is then secured by means of suit-
able screws to the hame immediately above
the groove 2 formed in said hame, thereby
firmly affixing all parts to the hame. The
upper end of the elongated slot in the plate 65
3 may, if desired, be suitably closed. The
tug being attached to the slidable member by
means of the bolt 11, said member is moved
up or down until the desired adjustment is
secured, when the pin 13 is passed through 70
the opening 9 in the lug 8 and thence through
one of the several openings 14 formed in the
plate 3 to one side of the elongated slot. In
order to lock the pin 13 in its position, one
end of the bolt 11 is passed through the eye 75
formed in the upper end of the pin 13, thereby
preventing said pin from becoming dis-
placed, as it would be impossible for the pin
to move out of engagement with the openings
in the lug 9 and the plate 3 until the bolt 11 80
is withdrawn.

What we claim, and desire to secure by Let-
ters Patent, is—

1. The combination with a hame of a groove
formed in one face thereof, of a plate secured 85
over said groove, an elongated slot formed in
said plate of less width than the groove in
the hame, a plate adapted to slide in said
elongated slot, wings extending laterally from
the bottom edge of said plate and lugs extend- 90
ing laterally from each end at the upper edge
of said plate, and means for securing said
plate in its adjusted position in said groove.

2. The combination of a hame having a
groove formed in one face thereof, of a plate 95
secured over said groove, an elongated slot
formed in said plate of less width than the
said groove, a series of openings formed
through said plate to one side of said elon-
gated slot, a plate adapted to slide in said 100
elongated slot, wings extending laterally from
the lower edge each side of said plate and

adapted to move in the groove in the hame, lugs extending upwardly and laterally from each end of the upper edge of said plate, said lugs extending beyond each side of the groove
5 formed in the hame, a perforated lug extending from one end of one of the last-named lugs, and a pin adapted to pass through said perforated lugs to the perforations in the plate secured to the hame, and a tug-bolt
10 adapted to pass through the end lugs and the

eye of said pin, all combined and operating as described.

The foregoing specification signed this 30th day of April, 1901.

EDDIE B. HAGOOD.
WILLIE D. ROLLINGS.

In presence of—
J. J. GRACE,
I. E. CONLEY.
